UNITED STATES PATENT OFFICE.

RICHARD ALLISON WATTS, OF KEO, ARKANSAS.

PAPER-SERVING APPARATUS.

No. 910,886.

Specification of Letters Patent.

Patented Jan. 26, 1909.

Application filed August 27, 1908. Serial No. 450,528.

To all whom it may concern:

Be it known that I, RICHARD ALLISON WATTS, a citizen of the United States, residing at Keo, in the county of Lonoke and State 5 of Arkansas, have invented certain new and useful Improvements in Paper-Serving Apparatus, of which the following is a specification.

This invention relates to store furniture, 10 and more particularly to serving apparatus, and has for its object to provide a device for serving wrapping paper which will be so constructed that after one length of papers has been cut therefrom, there will be a free end 15 portion of the paper to be grasped by the fingers when another length of paper is to be withdrawn from the device.

As shown in the drawings, the apparatus is 20 of the roll type, and is of simple construction so that it may be produced at a low figure.

Another object is to provide a cutting blade for attachment to paper roll apparatus already in use to produce the result attained by the present invention.

Other objects and advantages will be apparent from the following description, and it will be understood that changes in the specific structure shown and described may be made within the scope of the claims, without 30 departing from the spirit of the invention.

In the drawings forming a portion of this specification, and in which like numerals of reference indicate similar parts in the several views, Figure 1 is a front elevation of the 35 present invention, Fig. 2 is a detail perspective view of the guide and knife portions removed, Fig. 3 is a view showing the inner face of one of the standards. Fig. 4 is a detail sectional view of one of the standards showing 40 the mounting of the core.

Referring now to the drawings, the present invention includes two foot pieces 6, to which there are attached upwardly extending end standards 7. These standards are connected 45 at their upper ends by a horizontally extending top member 8, and at their center the standards are transversely enlarged as shown at 9 and are provided with alining horizontal openings 10.

The inner faces of the standards 7 are recessed to produce passages 11 communicating with the inner portion of the openings 10 and extending upwardly and forwardly as shown. Engaged in the openings 10 there 55 are a pair of arcuate plates 12, including spaced

edge portions 13 and a passage 14 therebetween, this passage 14 registering with the passage 11. Plugs 15 are engaged in the openings 10 over the inner portions of the plates 12 to hold the latter in position. These plates 60 thus produce bearings to receive the ends of a roll receiving core 16. This core is removable by disengagement of its ends through the openings 14 and the passages 11.

Hangers 17 in the form of staples, depend 65 from the top member 8, these hangers being arranged in pairs adjacent to either end of the top member and engaged with each pair of hangers there is a U shaped support 18 including a bight 19 received in the hangers, 70 and spaced downwardly and forwardly curved legs 20. Springs 21 are engaged with the bights 19 and are secured to the top member 8, these springs normally holding the forward ends of the support against upward movement. The forward ends just mentioned are attached to a transversely extending horizontal guide plate 22 which rests against the roll of paper 23, and which has downwardly and 75 inwardly directed guides 24 secured to its ends, these guides including horizontal portions 24' lying in spaced relation to the under edge of the guide plate 22. The horizontal portions 24' of course terminate short of each other, as shown in the drawings. It will be 80 understood that the paper from the roll is engaged between the guide plate 22 and the horizontal portions 24' of the guides 24.

Forwardly and downwardly curved rods 25 are detachably secured to the legs 20 of the 90 support 18 and these rods 25 are secured at their forward ends to a transversely extending horizontal knife 26, which by reason of the forward and downward curving of the rods 25 lies in spaced relation to the guide 95 plates 22 transversely of the roll 23 and also slightly below the guide plates 22. It will of course be understood that the knife blade 26 has its sharp edge directed downwardly. By reason of the detachable connection of 100 the rods 25 with the supports 18, these rods and therewith the knife 26 may be removed. The knife 26 and the rods 25 thus form an attachment which may be used in connection with paper rolls already in use, the rods 25 105 being secured to the usual support for the knife.

It will of course be understood that in use the free edge of the paper is drawn outwardly until a sufficient amount of paper has 110

been withdrawn from the roll, after which the paper is brought upwardly against the sharp edge of the knife 26. This action 5 severs the papers, but by reason of the space between the knife 26 and guide plate 22, there is a short length of papers extending downwardly after the cutting operation which may be grasped when more paper is to be removed from the roll.

10 What is claimed is:

1. In a paper serving apparatus, the combination with a standard having a transverse passage formed therethrough, and having a recess in its inner face communicating with the passage, said recess opening through one side face of the standard, of an arcuate plate engaged in the passage and extending into the recess, said plate having its edges disposed in spaced relation and being located with the space between its edges directed toward the face of the standard through which the recess opens, and a plug engaged within the arcuate plate and within the passage of the standard to hold 25 the plate in position.

2. In a paper serving apparatus, the com-

bination with a pair of parallel uprights, of a top member secured upon the uprights, staples engaged in the top member in pairs, a pair of said staples being located adjacent 30 to each end of the top member, a U-shaped member having its bight engaged in each pair of the staples, said members having spaced downwardly and forwardly curved legs, springs engaged with the bights between the 35 staples and engaging the top member, said springs being arranged to hold the free ends of the legs of the members yieldably against upward movement, a transversely extending horizontal guide connected with the lower 40 ends of said arms, a downwardly and forwardly extending rod connected with each of the arms, said rod extending below the guide, and a transversely extending knife carried by the lower ends of the rod below 45 the guide and outwardly thereof.

In testimony whereof I affix my signature, in presence of two witnesses.

RICHARD ALLISON WATTS.
